TAXI CAB

Dick H. Williams, Oak Park, Mich.

Application October 27, 1953, Serial No. 27,355

Term of patent 3½ years

(Cl. D14—3)

To all whom it may concern:

Be it known that I, Dick H. Williams, have invented a new, original, and ornamental Design for a Taxi Cab, of which the following is a specification, reference being had to the accompanying drawing, forming part thereof.

Fig. 1 is a side elevation of a taxi cab showing my new design.

Fig. 2 is a top plan view of the taxi cab shown in Fig. 1.

Figs. 3 and 4 are front and rear views respectively of the taxi cab shown in Fig. 1.

The dominant features of my design reside in the full line portions of the drawing.

I claim:

The ornamental design for a taxi cab, as shown and described.
